UNITED STATES PATENT OFFICE

JAMES H. BOYE, OF CHICAGO, ILLINOIS, ASSIGNOR TO JAMES H. BOYE MANUFACTURING COMPANY, OF CHICAGO, ILLINOIS, A CORPORATION OF ILLINOIS

DRAPE AND CURTAIN ROD SUPPORTING BRACKET

Application filed May 21, 1930. Serial No. 454,247.

This invention relates to a supporting bracket for curtain fixtures, and in its most complete form as hereinafter described and shown in the accompanying drawings, it constitutes an extensible support for both a drape rod and a curtain rod; the curtain rod support, however, may be usefully employed in a non-extensible bracket, while certain novel features of the extensible bracket may be employed independently of the use of a curtain rod support.

The main object of the invention is to provide a very simple, easily assembled and adjusted curtain fixture bracket of the character specified; and the novel structural features will be hereinafter fully described, and more particularly pointed out in the claims.

The invention, in its preferred form, is illustrated in the accompanying drawing in which—

Fig. 1 is a top plan view, showing the device adapted to support both a drape rod and a curtain rod.

Fig. 2 is a vertical section taken on the line 2—2 of Fig. 1.

Fig. 3 is a perspective view of the inner channel-shaped bracket arm.

Fig. 4 is a perspective view of the outer channel-shaped bracket arm and drape rod support on the outer end thereof.

Fig. 5 is a perspective view of the curtain rod support.

Referring to the drawing A may designate a portion of a window frame to which the bracket is attached. The inner section of the bracket arm is shown in detail in Fig. 3 and consists of a channel-shaped member 10 having at its rear end upper and lower flanges 11 and 12 apertured as shown for the passage of fastening screws 13. The vertical wall of the arm section 10 has a tapped hole to receive a clamp screw 14.

The outer arm section is shown in detail in Fig. 4 and comprises a channel-shaped member 15 of a size to slidably telescope over the arm section 10 and equipped on its outer end with a hollow seat or support 16 to receive one end of the drape rod 17. The vertical wall of the arm 15 is formed with a longitudinal slot 18 through which the clamp

screw 14 passes, and whereby the two arm sections 10 and 15 may be secured in adjusted position. On the rear end of the vertical wall of the outer arm section 15 is a laterally projecting handle member 19, by which, when the clamp screw is loosened, the outer arm section may be readily shifted back and forth over the inner arm section. The handle member is formed with a slot 20 that registers with the rear end of the slot 18 and is of sufficient size to permit the passage of the head of the clamp screw 14, so that by loosening the screw the two sections can be separated or combined without the necessity of withdrawing the clamp screw. The handle member 19 by connecting the portions of the arm above and below the slot 18 at the inner end of the arm, also maintains the arm rigid, while permitting the arm to be entered and withdrawn over the head of the clamp screw 14.

The described structure, it will be seen, readily enables the drape rod 17 to be positioned at varying distances from the window frame within the limits of adjustment of the inner and outer arm sections.

Describing now the curtain rod support, this element is shown in detail in Fig. 5 and comprises an inclined shank member 21 that, as shown in Fig. 1, is nested within the inner arm section 10 with its upper and lower edges in contact with the upper and lower flanges of the channel-shaped arm. The rear end of the shank member is formed with a hook 22 that engages over the rear edge of the vertical wall of the arm section 10 in the manner shown in Fig. 1, thus preventing any turning or twisting movement of the shank member 21 under the weight of the curtain rod and curtain. On the inner side of the forward end of the shank member 21 is a seat 23 into which the end of the curtain rod 24 is fitted as clearly shown in Fig. 2. On the outer side of the forward end of the shank member 21 is a spacing lug 24 that, as shown in Fig. 1, abuts against the inner side of the vertical wall of the inner arm section 10, to properly position the seat member 23 which projects from the inner side of the arm 10. It will readily be seen that when

the arm 10 is secured to the window frame, the hook 22 of the shank 21 is locked in place, so that the curtain rod support cannot become displaced.

5 Since the clamp screw 14 is located beyond the outer end of the curtain rod support, the latter does not interfere with the adjustment of the outer arm section carrying the drape rod support.

10 I claim:

1. A combined drape rod and curtain rod support, comprising a channel-shaped bracket arm attachable to a window frame formed on its outer end with a drape rod support, and
15 a curtain rod support comprising a shank member disposed within said bracket arm, in contact with the top and bottom flanges of the latter, and a seat member on the forward end of said shank member projecting from
20 the inner side of said bracket arm.

2. A combined drape rod and curtain rod support, comprising a channel-shaped bracket arm, attachable to a window frame formed on its outer end with a drape rod support, and
25 a curtain rod support comprising a shank member disposed within and lengthwise of said channel-shaped bracket arm and formed with a hook on its rear end engaging over
30 the rear end of the vertical wall of said bracket arm, and a seat member on the forward end of said shank member projecting from the inner side of said bracket arm.

3. A combined drape rod and curtain rod support, comprising a channel-shaped bracket arm attachable to a window frame formed on its outer end with a drape rod support, and a curtain rod support comprising an inclined shank member disposed within and lengthwise of said channel-shaped bracket
40 arm and formed on its rear end with a hook engaging over the rear end of the vertical wall of said bracket arm and on its forward end with a spacing lug abutting against the vertical wall of said bracket arm, and a seat member on the forward end of said shank member projecting from the inner side of said bracket arm.

4. A lengthwise adjustable rod-supporting bracket, comprising a channel-shaped inner section attachable to a window frame, a channel-shaped outer arm section slidable over said inner section, the vertical wall of said outer section having a longitudinal slot, a rod supporting member on the outer end of said outer section, a clamp screw passed through said slot and into said inner section, and a handle member projecting laterally from the rear end of the vertical wall of said outer section, said handle member formed
50 with a slot registering with the rear end of said longitudinal slot and of a size to permit the passage of the head of the clamp screw.

5. A combined extensible drape rod and
65 curtain rod support, comprising an inner

channel-shaped bracket arm section attachable to a window frame, an outer channel-shaped bracket arm section slidable over said inner section, a rod supporting member on the outer end of said outer section, means for clamping said sections in adjusted position, and a curtain rod support comprising a shank member disposed within and lengthwise of said inner section and formed with a hook on its rear end engaging over the rear end of the vertical wall of the inner section, and a seat member on the forward end of said shank member projecting from the inner side of said inner section.
